[57] CLAIM

The ornamental design for a belt mounted remote radio transmitter for signalling an operator of heavy equipment, substantially as shown and described.

DESCRIPTION

FIG. 1 is a top perspective view of a belt mounted remote radio transmitter for signalling an operator of heavy equipment showing my new design;
FIG. 2 is a left side elevational view thereof;
FIG. 3 is a right side elevational view thereof;
FIG. 4 is a rear elevational view thereof; and
FIG. 5 is a bottom plan view thereof.
